(57) **CLAIM**

The ornamental design for a rotary hand pump body, as shown and described.

DESCRIPTION

FIG. 1 is a perspective view of the rotary hand pump body. FIG. 2 is a front elevation view of the rotary hand pump body.

FIG. 3 is a first side elevation view of the rotary hand pump body.

FIG. 4 is a second side elevation view of the rotary hand pump body.

FIG. 5 is a rear elevation view of the rotary hand pump body.

FIG. 6 is a bottom view of the rotary hand pump body.

FIG. 7 is a top plan view of the rotary hand pump body.

FIG. 8 is a perspective view of the rotary hand pump body, with a hand crank shown in phantom.

FIG. 9 is a front elevation view of the rotary hand pump body, with the hand crank removed.

FIG. 10 is a first side elevation view of the rotary hand pump body, with a hand crank shown in phantom.

FIG. 11 is a second side elevation view of the rotary hand pump body, with a hand crank shown phantom.

FIG. 12 is a rear elevation view of the rotary hand pump body, with a hand crank shown in phantom.

FIG. 13 is a bottom view of the rotary hand pump body, with a hand crank shown in phantom; and,

FIG. 14 is a top plan view of the rotary hand pump body, with a hand crank shown in phantom.
